ELECTRIC SNAP SWITCH

George J. Meuer, Milwaukee, Wis., assignor to
Cutler-Hammer, Inc., Milwaukee, Wis., a corporation of Delaware

Application August 25, 1934, Serial No. 741,362
Renewed November 7, 1935

20 Claims. (Cl. 200—67)

This invention relates to improvements in electric snap switches, and although not limited thereto the invention relates more particularly to switches adapted for attachment to and for cooperation with radio rheostats or similar electrical devices.

A primary object of the invention is to improve and simplify the details of construction and assembly of the parts of the switch and the operation of the latter.

Another object is to provide a novel arrangement of parts enabling production of a switch of minimum depth or transverse dimension without sacrificing any of the desired structural or operative characteristics of the switch.

Another object is to provide a novel form and arrangement of the stationary and movable contact elements of the switch.

Another object is to provide a novel form of insulating carrier for the movable contactor or contactors of the switch.

Another object is to provide a novel form of actuating element for association with said carrier.

Another object is to provide a novel form of mounting means for the actuating element and the carrier.

Another object is to provide a switch having a minimum number of parts, certain of which parts are adapted for alternative use to provide switches having substantially different electrical functions or characteristics.

Other objects and advantages of the invention will hereinafter appear.

The accompanying drawing illustrates certain embodiments of the invention which will now be described, it being understood that the embodiments illustrated are susceptible of modification as to certain details thereof without departing from the scope of the appended claims.

In the drawing, Figure 1 is a plan view of the open end of a single-pole, single-throw snap switch constructed in accordance with my invention.

Fig. 2 is a sectional view, on the line 2—2 of Fig. 1,—the cover member for the wiring terminal elements being shown in position.

Fig. 3 is a plan view of the closed end of the switch shown in Figs. 1 and 2,—the aforementioned cover member being omitted, and a pair of conductors being shown in dotted lines as attached to the terminals.

Fig. 4 is a plan view of the open end of the insulating base shown in the preceding figures.

Fig. 5 is a view similar to Fig. 1, but showing a

modified form of insulating base and parts associated therewith to provide a snap switch of the double-pole, single-throw type.

Fig. 6 is a plan view of the closed end of the switch shown in Fig. 5.

Fig. 7 is a plan view of the open end of the insulating base shown in Figs. 5 and 6.

Fig. 8 is a fragmentary sectional view on the line 8—8 of Fig. 5.

Fig. 8a is a plan view of one of the switch contacts shown in Figs. 5 and 8.

Fig. 9 is a plan view of the open end of a further modified form of switch employing a base of the character shown in Fig. 5.

Fig. 10 is a sectional view on the broken line 10—10 of Fig. 9.

Fig. 11 is a sort of diagrammatic plan view, actual size, of the closed end of the switch shown in Figs. 9 and 10,—it being understood that in practice the insulating base is grooved in the manner shown in detail in Fig. 6, and

Fig. 12 is a detail perspective view of a contactor of the character illustrated in Figs. 1 and 5.

Referring first to Figs. 1 to 4, inclusive, the numeral 15 designates a molded insulating base 25 which is preferably composed of the phenol-formaldehyde condensation product sold commercially under the trade name of "bakelite". Base 15 is preferably of circular contour, and the same is recessed from one face thereof, as best illustrated 30 in Fig. 4, to provide an approximately circular bottom wall 15a and a relatively thin circumferential wall or cylindrical flange 15b. Base 15 is provided with an integral boss having a flat surface 15c located in a plane slightly above and 35 parallel with the plane of said bottom wall 15a (see Fig. 2). A flat punched plate 16 of impregnated fiber or other suitable insulating material of the form best illustrated in Fig. 1 is adapted to bear against said flat surface 15c. I prefer to 40 employ material consisting of a laminated phenolic sheet.

Plate 16 is provided with a relatively large opening 16a to afford clearance for a helical compression spring 17. Fitted into and adapted to 45 seat upon one end of spring 17 is a metal member 18 of concave form which bears against an abutment 16b formed in the wall of opening 16a. The other end of spring 17 is provided with a diametrically extending integral portion 17a the free end 50 of which extends slightly beyond the periphery of the spring coil (see Fig. 2) to facilitate insertion thereof into an opening provided in the downwardly offset portion 19a of an actuating element 19. Opening 16a likewise provides clear- 55

ance for said portion 19^a of the actuating element.

While I have shown the portion 19^a of actuating element 19 as being offset downwardly into the plane of plate 16, it is to be understood that if desired said portion 19^a may be located in the plane of the main body portion of element 19 while still providing for a substantially coplanar relationship of spring 17 and plate 16. Under these conditions the forwardly extending portion 19^a of element 19 will be made shorter to insure location of the spring-end-receiving opening therein at substantially the same radial distance from the pivot pin 20^a as is illustrated in the drawing. With either arrangement it will be apparent that spring 17 acts not only to effect snap movement of plate 16 from each extreme position thereof to the other, but said spring also effects a slight bias of the forward end of plate 16 toward the bottom wall 15^a of the recess, whereby proper engagement of contactor 29 with the rivet-head contact 21^a is insured.

Element 19 is preferably punched and stamped from sheet metal to the form best illustrated in Fig. 1,—the same being provided with laterally extending arms 19^b, 19^c of substantially triangular form which are adapted to alternately engage the circumferential wall 15^b of base 15 to limit the degree of pivotal movement of said element in each direction. Element 19 and plate 16 are respectively provided with circular openings of like size (see Fig. 2) to freely receive the pivot portion 20 of a pin which is provided with a relatively large head 20^a to prevent displacement of element 19 and plate 16 from said pivot portion.

The inner end of pivot portion 20 rests against the flat annular surface 15^d (Fig. 4) of a shallow depression formed in surface 15^c of the boss aforementioned, and said pin is provided with a reduced end 20^b which penetrates a corresponding opening 15^e in base 15 and is upset over the lower surface of the latter as shown at 20^c (Fig. 2) to permanently secure the aforementioned parts in assembled relation. The bottom wall 15^a is preferably provided with a recess 15^f to provide clearance for spring 17, and the bottom wall of recess 15^f is also preferably provided with a relatively smaller and relatively deeper recess 15^g to provide clearance for the edge portion of member 18.

The actuating element 19 is provided with a pair of upstanding parallel lugs 19^d, 19^e,—the upper ends of said lugs being of greater width than the lower ends thereof (see Fig. 2) and the forward portions of said upper ends being bent 55 or curved outwardly relatively to each other, as best illustrated in Fig. 1. Said lugs are adapted for alternate and transient engagement by an element (not shown) movable in an arcuate path and associated with the operating shaft of a 60 radio rheostat or the like. An arrangement of the character just referred to is disclosed in the copending application of myself and William C Stevens, Serial No. 587,774, filed May 16, 1931.

Base 15 is provided with integral abutments 15^x and 15^y to limit movements of plate 16 in opposite directions respectively. Base 15 is provided at a point diametrically opposed to the opening 15^e with an opening 15^h to accommodate the shank of a rivet 21 the head 21^a of which is 65 provided with a shoulder adapted to seat against the annular flat surface 15ⁱ provided by a slight depression surrounding said opening 15^h. Said head 21^a is provided with a flat circular contact surface spaced very slightly above the aforementioned bottom wall 15^a,—the periphery of head

21^a being beveled as shown in Fig. 2 to prevent stubbing of the contactor thereagainst, as hereinafter described.

Located within a shallow depression 15^j in the bottom surface of base 15 is a wiring terminal member 22 having a perforated lug portion 22^a which initially extends upwardly at a slight angle, as indicated in Fig. 3, to facilitate insertion and soldering of the bared end of a conductor (shown in dotted lines at 23). The shank 21 of the rivet is upset over terminal member 22 as shown at 21^b.

Secured to the upper surface of abutment 15^y, as by means of a rivet 24, is a resilient stationary contact member 25, the free and upwardly curved end portion 25^a of which is adapted to overlie and is biased toward the rivet head contact 21^a. Said bias is provided by downwardly bending contact 25 at the region of an opening or slot 25^b, which opening insures the desired degree of resiliency of said contact. Contact 25 is preferably provided with a small lug 25^c to fit within a correspondingly shaped notch or recess in base 15 to insure proper permanent positioning of said contact. The end 24^a of rivet 24 penetrates an opening in abutment 15^y and an opening in a wiring terminal member 26 and is upset over the latter as shown in Fig. 3. Member 26 is likewise provided with a perforated lug 26^a to receive for soldering the bared end of a wire shown in dotted lines at 27.

After the soldering operation the aforementioned lugs 22^a, 26^a are preferably bent downwardly into substantially flush relationship with the lower surface of base 15, and said base as shown is provided with grooves 15^k and 15^l to accommodate the wires 23 and 27. Base 15 is likewise preferably provided with shallow grooves 15^m, 15ⁿ to provide for employment of other types of wiring terminal members,—as, for instance, the types shown in Figs. 6 and 11. The type of wiring terminal members shown in Fig. 3, however, provides for concealment thereof by a simple form of insulating cover member of the character shown at 28 in Fig. 2. Said cover member has an annular flange 28^a to rest against the aforementioned lower surface of base 15, and the same is provided with openings (not shown) to register with the openings 15°, 15^p in base 15 through which pass the shanks of rivets or other fastening elements employed to secure the base to the metal cover member of a rheostat, or to another suitable form of support. Cover member 28 is preferably stamped or otherwise formed from a fiber plate and the same is shaped to accommodate the wires 23 and 27 and to provide for exit thereof as by means of grooves, one of which is shown at 28^b. As will be understood, the wire leads 23 and 27 of suitable or desired length will be attached to terminals 22 and 26 prior to attachment of cover member 28.

The inner edge of the annular wall 15^b of base 15 is preferably provided with a pair of relatively small substantially cylindrical integral projections 15^q and 15^r,—it being understood that the metal cover member of the rheostat (not shown) is provided with openings to receive said projections with a fairly close fit, whereby said projections cooperate with the fastening elements aforementioned to insure accurate and rigid positioning of base 15 relatively to its support. As best illustrated in Fig. 2 the aforementioned lugs 19^d, 19^e project upwardly beyond base 15,—the rheostat cover plate being of course provided with an opening to provide clearance for said lugs in 75

the manner disclosed in said Meuer and Stevens application Serial No. 537,774.

As shown in Fig. 1, the plate 16 is provided at a point adjacent to one end thereof, and at one side of the longitudinal center line thereof, with a through passage or opening 16^c of substantially elliptical contour. Said opening 16^c is adapted to accommodate with a snug or press fit the neck portion 29^a of a contactor 29 (see also Fig. 12) 5 whereby the shoulders 29^b, 29^c formed on said contactor are adapted to fit flatwise against the lower surface of plate 16. The upper end 29^e of contactor 29 is preferably curved or rounded as shown to facilitate movement thereof into and 15 out of engagement with the upwardly curved end 25^a of contact 25.

In like manner the relatively larger lower end of contactor 29 is preferably curved or rounded, as shown at 29^f, to facilitate sliding movement 20 thereof along the bottom wall 15^a of the recess in base 15, and to facilitate movement of said contactor 29 into and out of engagement with the head 21^a of rivet 21. Thus upon a given degree of movement of actuator 19 toward the right 25 (Fig. 1) the spring 17 will function in a well known manner to effect snap movement of contactor 29 into bridging engagement with contacts 21^a and 25 to complete the circuit controlled by the switch,—the aforementioned resiliency and 30 bias of contact 25 acting to insure the proper degree of pressure thereof against said contactor. Also obviously upon a given degree of movement of actuator 19 in the reverse direction, snap movement of the contactor to the "off" position 35 thereof illustrated in Fig. 1 will be effected.

Contactor 29 may be formed of any suitable conducting material, and I prefer to have the same composed of coin silver or other suitable silver alloy,—the part as illustrated being punched from a metal sheet of the required 40 thickness.

The plate 16 which is common to the devices illustrated in Figs. 1 and 5 is provided with a second elliptical opening 16^d, the same being adapted to receive a second contactor 29 in constructing a double-pole switch of the character 45 illustrated in Fig. 5.

As best illustrated in Fig. 2 the arrangement of a part 19^a of element 19 and spring 17 in substantially coplanar relationship with the flat contact-carrying plate 16 provides for a minimum depth of my complete snap switch. This feature is of considerable importance in view of the limited space available for combination volume 50 control and switch devices in the small or so-called "midget" radio receivers now on the market.

The switch illustrated in Figs. 5 to 8, inclusive, is structurally similar to that aforescribed and embodies certain of the parts shown in Figs. 1 to 60 3, which parts have been given like numerals of reference. Thus the contacting-carrying plate 16, the actuating element 19, spring 17, member 18, contact 25 and rivet 24, and the contactor 29 (shown in full lines) are preferably identical with 65 those parts aforescribed. The molded insulating base 30 is in general quite similar to the base 15 aforescribed and is recessed in a corresponding manner. In the device of Fig. 5, however, I employ a second contactor 29 (shown in dotted lines) and accordingly I provide a pair of stationary contacts 31 and 32 for cooperation with 70 said additional contactor 29.

Contact 31 is seated upon the ledge provided 75 by the top surface of an abutment 30^x (which

corresponds with the abutment 15^x of Fig. 1), said contact having a lug 31^a to fit into a suitable notch or recess in base 30 whereby said contact may be retained in fixed position, as by means of rivet 33. The hollow end of rivet 33 is upset 5 over the base portion of a terminal member 34 to secure the latter within a suitable groove or recess in the bottom surface of base 30, as best illustrated in Fig. 6.

The contacts 31 and 32 are preferably bent to 10 the respective forms thereof illustrated in Fig. 8 whereby said additional contactor 29 is disengaged from each of said contacts in one extreme position of plate 16, and engaged with each upon movement of plate 16 to its opposite extreme 15 position. Thus as shown in Fig. 8 the free and flexible ends 31^b and 32^a are normally biased toward each other and toward the opposite faces of plate 16, and said ends 31^b and 32^a are so formed as to facilitate movement of the upper 20 and lower curved end portions of contactor 29 into engagement therewith. Said additional contactor 29 when disengaged from contacts 31 and 32 is adapted to slidably engage the bottom wall 30^a of the main recess in base 30. 25

The contact 32, which is shown in detail in Fig. 8^a, is located within a correspondingly shaped recess in the bottom wall 30^a of the main recess in base 30. Contact 32 is provided with an opening 32^b to accommodate the shank of a rivet 35 30 which serves to secure said contact in position,—the hollow end of said rivet being upset over the base portion of a terminal member 36 to likewise secure the latter to the bottom surface of base 35 30 (see Fig. 6).

The rivet 21, of which the contact-head 21^a is shown in Fig. 5, has its hollow end upset over the base portion of a terminal member 37; and the rivet 24 aforesaid has its hollow end upset over the base portion of a terminal member 38,—one end of contact 25 being seated upon the ledge formed by the flat upper surface of an abutment 30^y. The terminal members 34, 36, 37 and 38 are preferably arranged in the manner best illustrated in Fig. 6, whereby the upstanding 45 perforated end portions thereof are located in planes substantially flush with the peripheral line or contour of base 30.

The lower surface of base 30 is preferably provided with additional or alternative grooves 30^b, 50 30^c, 30^d and 30^e to accommodate lead wires employed in conjunction with terminal members of the character illustrated at 22 and 26 in Fig. 3. When such lead wire terminals are employed in a switch of the character illustrated in Figs. 5 and 55 6, a fiber cover member similar to that shown at 28 in Fig. 2 (but having four properly located outlet grooves formed therein) may be employed,—the base 30 having through passages 30^f and 30^g to accommodate the shanks of rivets or 60 other fastening members (not shown). Cylindrical projections 30^h and 30ⁱ are likewise preferably provided on base 30 for a purpose heretofore explained in the description of the device shown in Fig. 1. 65

The forms of the main and auxiliary recesses in base 30 are best shown in Fig. 7,—the recess 30^j being adapted to provide clearance for spring 17, the recess 30^k being adapted to provide clearance for member 18 and the free end 32^a of contact 32, 70 and the recess 30^l being adapted to accommodate the main body portion of said contact 32. The contact head 21^a of rivet 21 is accommodated within the recess 30^m, and a portion of the aforedescribed pivot pin 20 is accommodated by the 75

annular recess 30^a formed in the flat upper surface 30^b of a boss located within the main recess in base 30 .

The operation of the switch is identical with the operation of the device in Fig. 1,—except that upon bridging engagement of contacts 21^a , 25 by one of the contactors 29 and other contactor 29 will simultaneously engage contacts 31 and 32 , and disengagement of contactors 29 from said pair of contacts will likewise be effected simultaneously.

In constructing the multiple-circuit-controlling switch illustrated in Figs. 9, 10 and 11 I may employ an insulating base 30 identical with that illustrated in Figs. 5 to 8, and corresponding parts of the base are designated by like reference numerals. Also the actuating element 19 , spring 17 , member 18 and rivets 24 and 33 are identical with those parts in Fig. 5.

The flat punched plate 39 of insulating material is substantially like the plate 16 aforescribed. However, the plate 39 is provided with a single substantially elliptical opening 39^c adjacent to the free end thereof and in symmetrical relationship to the longitudinal center line of the plate. I provide a contactor 40 the reduced upper end portion 40^a of which is insertable upwardly with a press fit through said opening 39^c , as best illustrated in Fig. 10. Contactor 40 is provided with a relatively wide lower end portion 40^b which is adapted for continuous engagement with the contact-head 21^a of rivet 21 , as best illustrated in Fig. 10.

Left-hand and right-hand contacts 41 and 42 are secured to the upper surfaces of abutments 30^y and 30^z , as by means of the rivets 24 and 33 , said contacts being relatively shorter than the contact 25 aforescribed. The arrangement is such that in one extreme position of contactor 40 the same is adapted to bridge contact 42 and contact-head 21^a (as shown in Figs. 9 and 10), and in the other extreme position said contactor is adapted to bridge contact 41 and said contact-head 21^a .

The hollow ends of rivets 24 , 21 and 33 are upset over terminal members 43 , 44 and 45 , respectively,—said terminal members preferably being of flat form, as best illustrated in Fig. 11, whereby the same project laterally beyond the circumference of base 30 . Said terminal members are each provided with a relatively large and a relatively small opening in that portion thereof extending beyond base 30 , as indicated at 43^a and 43^b in Fig. 11. Said opening 43^a is preferably of a size to permit attachment of two or more wires as by soldering. The primary purpose of the small opening 43^b is to limit or minimize the amount of heat transmitted through the terminal member as an incident to the soldering operation, and to localize any bending strains imposed upon the terminal members either accidentally or otherwise. In practice the terminal members 43 and 45 are respectively associated with different circuits, whereas the terminal member 44 is common to said circuits.

The reference character 30^p in Figs. 9 and 11 designates a diaphragm or relatively thin film of the material of base 30 , said diaphragm being produced by the molding operation. In utilizing base 30 for construction of a switch like that illustrated in Figs. 9 to 11 said diaphragm is left intact to insure a dust-proof enclosure for the movable parts of the switch upon attachment of the latter to a rheostat housing or other suitable support. When base 30 is employed to construct

a switch requiring use of the securing member 35 (as in Fig. 5) the aforescribed diaphragm 30^p is removed by a broaching operation, or by forcibly inserting said member 35 to effect removal of said diaphragm.

As aforescribed, the base 30 of Fig. 11 is in practice provided with the various grooves shown in detail in Fig. 6, whereby terminal elements of the character illustrated in connection with each of the other types of switches may be alternatively employed.

What I claim as new and desire to secure by Letters Patent is:

1. In an electric snap switch, in combination, a molded insulating base having a relatively shallow recess formed therein, a flat punched plate of insulating material located within said recess and oscillatable in a plane parallel to but spaced from the bottom wall of said recess, said plate having a relatively large opening formed therein, an actuating element, a pivot pin common to said actuating element and said plate, a helical compression spring interposed between a portion of said actuating element and said plate, said spring being arranged within said opening in substantially coplanar relationship to said plate, a pair of stationary contacts located within said recess, one of said contacts comprising a metal member the flat head portion of which projects slightly above the bottom wall of said recess, the other of said contacts comprising a resilient arm positioned above and biased toward said head portion, and a punched sheet metal contactor carried by said plate and movable therewith into and out of bridging engagement with said contacts.

2. In an electric snap switch, in combination, a molded insulating base having a relatively shallow recess formed therein, a flat punched plate of insulating material located within said recess and oscillatable in a plane parallel to the bottom wall of said recess, said plate having a relatively large opening of substantially frustoconical contour, an actuating element, a pivot pin common to said actuating element and said plate, a helical compression spring interposed between a portion of said actuating element and said plate, said spring being arranged within said opening in substantially coplanar relationship to said plate, a pair of stationary contacts located within said recess, one of said contacts comprising a metal member the flat head portion of which projects above the bottom wall of said recess, the other of said contacts comprising a resilient arm, a punched sheet metal contactor carried by said plate and movable therewith into and out of bridging engagement with said contacts, and said base having abutments formed integrally therewith to limit the oscillatory movements of said plate.

3. In an electric snap switch, in combination, a molded insulating base having a relatively shallow recess formed therein, a flat punched plate of insulating material located within said recess and oscillatable in a plane parallel to but spaced from the bottom wall of said recess, said plate having a relatively large opening formed therein, an actuating element, a pivot pin common to said actuating element and said plate, a helical compression spring interposed between a portion of said actuating element and said plate, said spring being arranged within said opening in substantially coplanar relationship to said plate, a pair of stationary contacts located within said recess, a punched sheet metal contactor carried

by said plate and movable therewith into and out of bridging engagement with said contacts, said plate having a relatively small substantially elliptical opening formed therein adjacent to the free end thereof, said contactor being forcibly insertable upwardly through said last mentioned opening and having edge portions thereof exposed on opposite faces of said plate, said insulating base having a pair of abutments formed integrally therewith and located within said recess, and said insulating plate being alternately engageable with said abutments to positively limit movements of said plate in opposite directions respectively.

4. In an electric snap switch, in combination, a molded insulating base of substantially circular contour, said base being of relatively shallow depth and being recessed from one face thereof throughout the major portion of its area, a boss formed integrally with the bottom wall of said recess and having a flat surface spaced upwardly from said bottom wall, a flat punched plate of insulating material of substantially loop-shape, one end of said plate being adapted to bear flatwise against said flat surface, a punched and stamped sheet metal actuating element having a portion thereof seated flatwise upon said end of said plate, said element also having a portion thereof offset downwardly to lie substantially within the plane of said plate, said plate having an abutment formed on the interior wall of said loop, a helical compression spring interposed between said abutment and said downwardly offset portion, a pivot pin extending downwardly through said actuating element, said end of the plate and said insulating base and upset over the outer surface of the latter, said pin having an element associated therewith to retain said parts in assembled relation, said insulating plate having a relatively small opening formed therein adjacent to the free end thereof, a metal contactor located within said opening and having portions thereof exposed on opposite faces of said plate, the lower end of said contactor being adapted to slidably engage the bottom wall of said recess, and a pair of upper and lower stationary contacts between which said insulating plate is interposed, said contactor being movable with said plate into and out of bridging engagement with said contacts.

5. In an electric switch, in combination, a recessed molded insulating base, a pivot pin attached to said base at a point adjacent to the periphery of the recess, a contact carrier and an actuating element oscillatably supported by said pin, said contact carrier comprising a flat punched plate of insulating material, said plate having a relatively large opening of substantially frusto-conical contour, said actuating element having a portion thereof extending downwardly into the plane of said plate, the forward wall of said opening being formed to provide a spring abutment, a helical compression spring interposed between said abutment and said downwardly extending portion of said actuating element, the walls of said opening providing clearance for said spring and said downwardly extending portion, a contactor rigidly attached to said plate adjacent to the free end thereof and having portions thereof exposed on opposite faces of said plate, and a pair of upper and lower stationary contacts into and out of bridging engagement with which said contactor is adapted to move with a snap action upon opposite movements respectively of said actuating element.

6. In an electric switch, in combination, a re-

cessed molded insulating base, a pivot pin attached to said base at a point adjacent to the periphery of the recess, a contact carrier and an actuating element oscillatably supported by said pin, said contact carrier comprising a flat punched plate of insulating material having a contact-receiving opening formed therein adjacent to the free end thereof, said plate also having a relatively larger intermediate opening of substantially frusto-conical contour, said actuating element having a portion thereof offset downwardly into the plane of said plate, the forward wall of said intermediate opening being formed to provide a spring abutment, a helical compression spring interposed between said abutment and said downwardly offset portion of said actuating element, the walls of said intermediate opening providing clearance for said spring and said downwardly offset portion, a contactor comprising a flat punched sheet metal member forcibly insertable upwardly through said contact-receiving opening and having portions thereof exposed on opposite faces of said plate, a pair of upper and lower stationary contacts into and out of bridging engagement with which said contactor is adapted to move with a snap action upon opposite movements respectively of said actuating element, and the bottom wall of said first-mentioned recess having an auxiliary recess formed therein to provide clearance for said compression spring.

7. An electric snap switch comprising, in combination, a relatively shallow molded insulating base, said base being recessed from one face thereof throughout the major portion of its area, a pivot pin located at one end of the recess in said base, a flat punched insulating plate and a sheet metal actuating element arranged in superimposed relation and jointly supported by said pivot pin, said plate having a relatively large opening formed therein, the forward wall of said opening being formed to provide a spring abutment, a helical compression spring interposed between said abutment and said actuating element, a punched sheet metal contactor carried by said plate and having portions thereof exposed on opposite faces of said plate, a pair of upper and lower contacts located within said recess, said contactor being movable with a snap action into and out of engagement with said contacts upon opposite movements respectively of said actuating element, wiring terminal elements electrically and mechanically connected with the respective contacts and located in spaced relation upon the bottom surface of said base, said bottom surface of said base having grooves formed therein to partially accommodate the respective terminal wires, and a shallow cup-shaped insulating cover member seated against said bottom surface of said base, said cover member and said base having registering openings to accommodate suitable fastening members whereby said base and cover member may be secured to each other and to a suitable support.

8. An electric snap switch comprising, in combination, a relatively shallow molded insulating base, said base being recessed from one face thereof throughout the major portion of its area, a pivot pin located at one end of the recess in said base, a flat punched insulating plate and a sheet metal actuating element arranged in superimposed relation and jointly supported by said pivot pin, said plate having a relatively large opening formed therein and said actuating element having a portion thereof offset downwardly for oscillatory movement thereof within said

opening, the forward wall of said opening being formed to provide a spring abutment, a helical compression spring interposed between said abutment and said offset portion, a sheet metal contactor carried by said plate and having portions thereof exposed on opposite faces of said plate, a pair of upper and lower contacts located within said recess, said contactor being movable with a snap action into and out of engagement with said contacts upon opposite movements respectively of said actuating element, wiring terminal elements electrically and mechanically connected with the respective contacts and located in spaced relation upon the bottom surface of said base, said bottom surface of said base having grooves formed therein to partially accommodate the respective terminal wires, and said bottom surface of said base having additional grooves formed therein to alternatively accommodate different forms of wiring terminal elements.

9. As an article of manufacture, a flat punched sheet metal contactor for electric snap switches, said contactor having a relatively wide lower end portion having a curved lower edge and a relatively narrower upper end portion having a curved upper edge, and said lower and upper end portions having a pair of horizontal shoulders formed therebetween to limit upward displacement of said contactor when assembled with an insulating carrier member of suitable form.

10. As an article of manufacture, an actuating element for electric snap switches, said element comprising a punched and stamped sheet metal member having a flat base portion of substantially triangular contour, the apex of the triangle being rounded, said base portion having a pivot opening located substantially centrally thereof, the ends of said base portion on opposite sides of said pivot opening being adapted for engagement with suitable abutments to limit the degrees of oscillatory movement of said actuating element in opposite directions respectively, said base portion having a relatively narrow forward extension provided with a perforation to act as a spring abutment, and said forward extension having a pair of lugs formed integrally therewith and bent upwardly into substantially parallel relationship to each other, the upper ends of said lugs being relatively wider than the lower ends thereof and the forward portions of said upper ends being bent outwardly from each other to provide for transient engagement thereof alternately by an oscillatable operating member of suitable form.

11. As an article of manufacture, an actuating element for electric snap switches, said element comprising a punched and stamped sheet metal member having a flat base portion of substantially triangular contour, the apex of the triangle being rounded, said base portion having a pivot opening located substantially centrally thereof, the ends of said base portion on opposite sides of said pivot opening being adapted for engagement with suitable abutments to limit the degrees of oscillatory movement of said actuating element in opposite directions respectively, said base portion having a relatively narrow forward extension and said extension having a perforated lug offset downwardly with respect thereto to provide a spring abutment, and said forward extension having a pair of lugs formed integrally therewith and bent upwardly into substantially parallel relationship to each other, the upper ends of said lugs being relatively wider than the lower ends thereof and the forward portions of said up-

per ends being bent outwardly from each other to provide for transient engagement thereof alternately by an oscillatable operating member of suitable form.

12. In an electric snap switch, in combination, a relatively shallow molded insulating base, said base being recessed from one face thereof throughout the major portion of its area, the bottom wall of said recess having a flat-faced boss formed thereon at one end thereof, a flat punched plate of insulating material adapted to bear against the flat face of said boss, a punched and stamped sheet metal actuating element having a flat portion thereof superimposed upon said plate, a pin rigidly secured to said insulating base and adapted to pivotally support said actuating element and said plate, said plate having a relatively large cut-away portion intermediate the length thereof, said actuating element having a lug offset downwardly from said flat portion thereof and adapted to lie within the plane of said plate, an abutment formed in the wall of said cut-away portion at the forward end of the latter, a helical compression spring interposed between said abutment and said lug, said recess having abutments formed therein to limit the degree of oscillatory movement of said plate in each direction, said actuating element having arms alternately engageable with the wall of said recess to limit the degree of oscillatory movement of said actuating element in each direction, said actuating element also having a pair of spaced upstanding lugs to be transiently engaged alternately by an operating element of suitable form, a pair of flat punched sheet metal contactors carried by said plate at points spaced different distances from the point of pivotal support of the latter, said contactors each having portions thereof exposed upon the upper and lower surfaces of said plate, two pairs of upper and lower stationary contacts, said contactors being simultaneously engageable with and simultaneously disengageable from the upper and lower contacts of said pairs, and four wiring terminal members electrically and mechanically connected with the respective stationary contacts and exposed upon the bottom surface of said base.

13. In an electric snap switch, in combination, a relatively shallow molded insulating base, said base being recessed from one face thereof throughout the major portion of its area, the bottom wall of said recess having a flat-faced boss formed thereon at one end thereof, a flat punched plate of insulating material adapted to bear against the flat face of said boss, a punched and stamped sheet metal actuating element having a flat portion thereof superimposed upon said plate, a pin rigidly secured to said insulating base and adapted to pivotally support said actuating element and said plate, said plate having a relatively large cut-away portion intermediate the length thereof, said actuating element having a lug offset downwardly from said flat portion thereof and adapted to lie within the plane of said plate, an abutment formed in the wall of said cut-away portion at the forward end of the latter, a helical compression spring interposed between said abutment and said lug, said recess having abutments formed therein to limit the degree of oscillatory movement of said plate in each direction, said actuating element having arms alternately engageable with the wall of said recess to limit the degree of oscillatory movement of said actuating element in each di-

rection, said actuating element also having a pair of spaced upstanding lugs to be transiently engaged alternately by an operating element of suitable form, a flat punched sheet metal contactor located at the mid-point of the width of said plate adjacent to the forward end of the latter, said contactor having a relatively narrow edge portion exposed upon the upper surface of said plate and a relatively wider edge portion exposed upon the lower surface of said plate, a pair of resilient stationary contacts supported upon the upper surfaces of said recess abutments respectively and having the free ends thereof alined with and spaced from each other, said relatively narrow edge portion of said contactor being engageable with said contacts alternately upon movement of plate to opposite extreme positions respectively, a rivet-head contact having a flat upper surface located slightly above the bottom wall of said recess, said relatively wider edge portion of said contactor being slidable across said flat upper surface but engaged with the latter in each extreme position of said plate, and three wiring terminal members electrically and mechanically connected with the respective contacts and exposed upon the lower surface of said base.

14. In an electric snap switch, in combination, a relatively shallow molded insulating base, said base being recessed from one face thereof throughout the major portion of its area, a boss formed integrally with the bottom wall of said recess and having a flat surface spaced upwardly from said bottom wall, a flat plate of insulating material of substantially loop-shape, one end portion of said plate being adapted to bear flatwise against said flat surface, a punched and stamped sheet metal actuating element having a portion thereof seated flatwise upon said end portion of said plate, said element having its forward end portion formed to provide a spring abutment, said plate having a spring abutment formed on the interior wall of said loop at the forward end of the latter, a helical compression spring interposed between said abutments and arranged in a substantially coplanar relationship to said plate, a pivot pin extending downwardly through said actuating element, said end portion of the plate and said boss, the lower end portion of said pin being upset over the outer surface of said base, said pin having an enlarged head formed thereon to retain said parts in assembled relation, said insulating plate having a relatively small opening formed therein adjacent to the free end thereof, a metal contactor located within said opening and having portions thereof exposed on opposite faces of said plate, and a pair of upper and lower stationary contacts between which said insulating plate is interposed, at least one of said contacts being resilient, said contactor being movable with said plate with a snap action into and out of bridging engagement with said contacts.

15. In an electric switch, in combination, a recessed molded insulating base, a pivot pin attached to said base at a point adjacent to the periphery of the recess, a contact carrier and an actuating element oscillatably supported by said pin, said contact carrier comprising a flat punched plate of insulating material having a contact-receiving opening formed therein adjacent to the free end thereof, said plate also having a relatively larger intermediate opening of substantially frusto-conical contour, the forward end portion of said actuating element having a

relatively small opening formed therein to provide a spring abutment, a helical compression spring having a diametrically extending portion at one end thereof, said diametrically extending portion being inserted into said relatively small opening, the forward wall of the intermediate opening in said plate being formed to provide a spring abutment, the other end of said spring being engaged with said last mentioned abutment, the walls of said intermediate opening providing clearance for said spring, a contactor comprising a sheet metal member insertable through said contact-receiving opening and having portions thereof exposed on opposite faces of said plate, a rigid lower stationary contact and an upper resilient stationary contact into and out of bridging engagement with which said contactor is adapted to move with a snap action upon opposite movements respectively of said actuating element, and the bottom wall of said first mentioned recess having an auxiliary recess formed therein to provide clearance for said compression spring.

16. As an article of manufacture, an actuating element for electric snap switches, said element comprising a punched and stamped sheet metal member having a flat base portion of substantially triangular contour, said base portion having a pivot opening located substantially centrally thereof, the ends of said base portion on opposite sides of said pivot opening being adapted for alternate engagement with suitable abutments to limit the degrees of oscillatory movement of said actuating element in opposite directions respectively, said base portion having a relatively narrow forward extension and said extension having a perforated lug formed integrally therewith to provide a spring abutment, and said forward extension having a pair of additional lugs formed integrally therewith and bent upwardly into substantially parallel relationship to each other, the upper ends of said pair of lugs being relatively wider than the lower ends thereof and the forward portions of said upper ends being bent outwardly from each other to provide for transient engagement thereof alternately by an oscillatable operating member of suitable form.

17. In an electric snap switch, in combination, an insulating base, a pivot pin attached to said base at a point adjacent to the periphery thereof, a contactor carrier and an actuating element oscillatably supported by said pin, said contactor carrier comprising a flat punched plate of insulating material, said plate having a relatively large opening formed therein intermediate the ends thereof, means at the end wall of said opening remote from the pivot pin to provide an abutment for a coiled compression spring, said actuating element having an abutment portion thereof located within the area of said opening, a coiled compression spring interposed between said abutments, the walls of said opening providing clearance for said spring during movement of the latter as an incident to oscillatory movements of said actuating element and said plate, a contactor carried by said plate adjacent to the free end thereof, said contactor having portions thereof exposed on opposite faces of said plate, and a pair of upper and lower stationary contacts into and out of bridging engagement with which said contactor is adapted to move with a snap action upon opposite movements respectively of said actuating element, at least one of said contacts being resilient.

18. In an electric snap switch, in combina- 75

tion, an insulating base, a pivot pin rigidly attached to said base, a flat punched plate of insulating material pivotally supported by said pin for oscillation in a plane parallel to but spaced 5 from a surface of said base, a punched and stamped sheet metal actuating element superimposed upon said plate and also pivotally supported by said pin, said plate having a relatively large opening formed therein, a coiled compression spring interposed between a portion of said actuating element and said plate, said spring being arranged within said opening in substantially coplanar relationship to said plate, a pair of stationary contacts positioned upon said base, 10 one of said contacts comprising a metal member a portion of which is exposed at the aforementioned surface of said base, the other of said contacts comprising a resilient arm positioned above and biased toward the exposed portion of 15 said metal member, a contactor penetrating said plate and movable thereby into and out of bridging engagement with said contacts, and means associated with said plate and said actuating element to positively limit movements thereof in 20 opposite directions respectively.

19. In an electric snap switch, in combination, an insulating base, a flat plate of insulating material of substantially loop-shape, said plate being arranged in parallel spaced relation to said 25 base and oscillatable with respect thereto, a punched and stamped sheet metal actuating element having a portion thereof seated flatwise upon said plate, said element having a portion thereof formed to provide a spring abutment, said 30 plate having a spring abutment at one end of said loop, a coiled compression spring interposed between said abutments and arranged in a substantially coplanar relationship to said plate, a pivot pin extending through said actuating element, said plate and said base, the lower end 35 portion of said pin being upset over the lower surface of said base, said insulating plate having a relatively small opening formed therein adja-

cent to the free end thereof, a metal contactor located within said opening and having portions thereof exposed on opposite faces of said plate, and a pair of upper and lower stationary contacts between which said insulating plate is interposed in all positions of the latter, at least one of said contacts being resilient, said contactor being movable with said plate with a snap action into and out of bridging engagement with said contacts. 10

20. In an electric snap switch, in combination, a substantially circular insulating base, a pivot pin attached to said base at a point adjacent to the periphery thereof, a contactor carrier and an actuating element oscillatably supported by 15 said pin, said contactor carrier comprising a flat punched plate of insulating material having a contactor-receiving opening formed therein adjacent to the free end thereof, said plate also having a relatively larger intermediate opening 20 of substantially frusto-conical contour, the forward end portion of said actuating element having a relatively small opening formed therein to provide a spring abutment, a coiled compression 25 spring having a diametrically extending portion at one end thereof, said diametrically extending portion being inserted into said relatively small opening, a spring abutment at the forward end wall of the intermediate opening in said plate, the other end of said spring being engaged with said 30 last mentioned abutment, the walls of said intermediate opening providing clearance for said spring, a contactor insertable through said contact-receiving opening and having portions thereof exposed on opposite faces of said plate, a rigid lower stationary contact and an upper resilient stationary contact into and out of bridging engagement with which said contactor is adapted 35 to move with a snap action upon opposite movements respectively of said actuating element, and 40 said base having a recess formed therein to provide clearance for said compression spring.

GEORGE J. MEUER.
